(57) **CLAIM**

The ornamental design for a artificial plant holder, as shown and described.

DESCRIPTION

FIG. 1 is a perspective view of the artificial plant holder;
FIG. 2 is an exploded perspective view of the insert and tray
components of the artificial plant holder;
FIG. 3 is a side view of the tray, the sides being the same;
FIG. 4 is an end view of the tray, the ends being the same;
FIG. 5 is a top view of the artificial plant holder;
FIG. 6 is a bottom view of the artificial plant holder;
FIG. 7 is a side view of the insert, the sides being the same;
FIG. 8 is an end view of the insert, the ends being the same;
and,
FIG. 9 is a bottom view of the insert.
The insert shown in FIGS. 7, 8, and 9 is shown separately
for convenience of illustration.
